(57) **CLAIM**

The ornamental design for a beverage brewer, as shown and described.

DESCRIPTION

FIG. 1 is a front isometric view of a beverage brewer showing our new design, with a cup tray in the deployed position;

FIG. 2 is a rear isometric view of the beverage brewer of FIG. 1;

FIG. 3 is a left side elevation view of the beverage brewer of FIG. 1;

FIG. 4 is a front elevation view of the beverage brewer of FIG. 1;

FIG. 5 is a right side elevation view of the beverage brewer of FIG. 1;

FIG. 6 is a rear elevation view of the beverage brewer of FIG. 1;

FIG. 7 is a top plan view of the beverage brewer of FIG. 1;

FIG. 8 is a bottom plan view of the beverage brewer of FIG. 1; and,

FIG. 9 is a front isometric view of the beverage brewer of FIG. 1, with the cup tray in retracted position.

The design is the visual features of the beverage brewer shown in the drawings, whether those features are features of one of shape, configuration, ornament or pattern or are a combination of any of these features.

The broken lines in the drawing depict portions of the beverage brewer that form no part of the claimed design.
